UNITED STATES PATENT OFFICE

97,102

DESIGN FOR A JAR

Frasier Smith, Wheeling, W. Va., assignor to
Hazel-Atlas Glass Company, Wheeling, W. Va.,
a corporation of West Virginia

Application July 31, 1935, Serial No. 57,885

Term of patent 7 years

To whom it may concern:

Be it known that I, Frasier Smith, a citizen of the United States, residing at Wheeling, in the county of Ohio and State of West Virginia, have invented a new, original, and ornamental Design for a Jar, of which the following is a specification, reference being had to the accompanying drawing, forming part thereof.

Figure 1 is a front elevational view of a jar showing my new design; and

Figure 2 is a side elevational view thereof.

I claim:

The ornamental design for a jar, as shown.

FRASIER SMITH.
